UNITED STATES PATENT OFFICE.

LEWIS L. SCOTT, OF ST. LOUIS, MISSOURI, ASSIGNOR TO STANDARD ENGINEERING COMPANY, OF ST. LOUIS, MISSOURI, A CORPORATION.

STEAM-GENERATING SYSTEM.

1,385,845.

Specification of Letters Patent. Patented July 26, 1921.

Application filed February 8, 1918. Serial No. 216,024.

To all whom it may concern:

Be it known that I, LEWIS L. SCOTT, a citizen of the United States, residing in the city of St. Louis, Missouri, have invented a 5 new and useful Improvement in Steam-Generating Systems, of which the following is a specification.

This invention is constructed with especial reference to its use upon steam driven 10 automobiles, by means of which to automatically so control the delivery of fuel to the combustion chamber, and water to the generator, that steam shall be generated in said generator in the volume necessary to 15 meet the varying demands therefor, and shall be maintained in substantially uniform condition as to pressure and temperature. The specific embodiment of the invention shown is contrived with special reference to its use in connection with a steam 20 generator of the semi-flash type.

Regulators for use in semi-flash boilers have heretofore been devised which, theoretically, should give perfect results; but in 25 actual practice they do not, because of their sluggish action and because of the time required to realize the effects caused by the action of said regulators. Overheating of the generator or flooding same with water 30 is the usual result, unless the regulators are assisted manually by a skilled operator.

One object of my invention is to provide a steam generating system that can be put into operation by the closing of an electric switch, and to provide automatic devices for such system which will keep the steam at a constant pressure and temperature regardless of the sudden changes in demand for steam. A further object is to 35 make said devices instantaneous in their action, so that when there is a sudden call for a large amount of steam there will be no material drop in the steam pressure. A further object is to provide safety devices for 40 the steam generating system which will automatically shut off the fire, if the water tank is empty, or will shut off the water from the generator if the fuel tank is empty, and further to provide a system in which 45 heavy hydro-carbon fuel can be ignited at normal temperature by electric ignition means, and so arranged that if the electric device fails, unburned fuel cannot be forced into the combustion chamber and water can- 50 not be forced to the generator coils. In

other words, it is a system that can be used by the average unskilled driver of an automobile, without fear of damage to any part of said system, and without fear of danger to the operator of said automobile. 60

In the accompanying drawings, Figure 1 is a diagram of parts and connections illustrating one embodiment of my invention,

Fig. 2 is an end view of a sparking device used for igniting the fuel mixture in the 65 combustion system,

Fig. 3 is a side view of one of the elements of said sparking device.

Referring to the drawings, 1 represents the steam generating coils of a semi-flash 70 boiler such as shown in Patent No. 659,837 to R. H. White. 2 is a continuous tube pre-heating coil which is connected to the steam generator coils through the check valve 3, said check valve allowing water to pass 75 from the preheating coil to the generating coils. 4 is a steam storage coil, one end of which is connected to the steam outlet pipe 5 through the blow off valve 6 (said blow off valve being set to allow steam to pass from 80 the generating coils 1 to the steam storage coil 4, when the pressure in said generator coils 1 has reached a predetermined amount and when steam is being generated in coils 1 in excess of the demand therefor) and the 85 other end of the steam storage coil 4 is connected to the steam generating coils 1 through the check valve 7 at any convenient point such as shown at 8. It will be noted that at no time will the steam storage coil 90 rob the generator coils 1 of steam, or in any way interfere with the regular generating of steam in said generating coils 1. The purpose of said steam storage coil is to fill in the gap of the few seconds required 95 for the fire to become effective (once said fire has been automatically shut off and there comes a sudden demand for steam) by returning the steam stored in said storage coil to the generator coils 1, when the pressure in said generator coils drops below the pressure 100 in the steam storage coil. This action is entirely automatic.

The pipe 9 is connected to the steam storage coil and runs to the Bourdon tube 10. 105 Said Bourdon tube 10 acts, at a predetermined pressure in the steam storage coil, to open an electric switch. The purpose of such action will be described later.

The steam generator coils, steam storage 110

- coils and the preheating coils are all inclosed by a suitable refractory heat insulating material, the steam generator coils being separated from the steam storage and preheating coils by the partition 11 which forms two compartments; said partition being made of refractory material and terminating short of the top of the casing inclosing the coils and providing communication between the two compartments for the products of combustion which pass out of the casing at the lower part of the compartment containing the preheating and steam storage coils.
- 15 The steam outlet pipe 5 connects, through a suitable throttle valve 12, to the steam engine 13. The exhaust pipe 14 of said engine is preferably run through the water tank 15 (for the purpose of cooling the exhaust steam and heating the water in said tank) to a suitable steam condenser, not shown.

For supplying water to the steam generator I use two plunger water pumps 16 and 17. While both of these pumps may be driven from the steam engine, I prefer in some cases, to drive the pump 16 from the steam engine and the pump 17 by an electric motor 18. The numeral 19 indicates a worm, on the electric motor shaft 19^a, which drives the worm wheel 20; said worm wheel carrying the crank pin 21 which connects to the piston of the pump 17, through the rod 22. The pump 17 is provided with the usual check valves 23 and the pump 16 is likewise provided with the check valves 24. The intake pipe 25, to the pumps, connects with the lower part of the water tank 15. The discharge pipe 26, from the pumps, connects to the lower end of the preheating coil 2.

An air compressor 27 is preferably driven from the steam engine 13 (although it may be driven by an electric motor) and furnishes air at high pressure to the tank 28; said air tank 28 is provided with a hand pump 29. Air from the tank 28 passes through the reducing valve 30, which allows air to flow from the tank at a low and constant pressure, and enters the pipes 31 and 32. The pipe 31 leads to the top of the fuel tank 33 and forces the fuel in said tank to the float valve 34. The pipe 32 leads to the air nozzle 35, which nozzle serves the purpose of atomizing fuel from the fuel nozzle 36, said fuel nozzle being connected to the float valve 34. While I have shown but one air and one fuel nozzle, any number of these nozzles may be used as desired.

60 The atomized fuel is ignited by the spark plug 37; said spark plug being connected to the high tension winding 38 of a vibrating spark coil.

As before stated, I prefer to use a heavy hydro carbon liquid fuel, such as kerosene,

which is atomized as before described, and ignited at normal temperature by the electric spark. I have found that there are certain conditions which regulate the initiation of combustion (by an electric spark) 70 of a mixture of air and atomized kerosene, i. e., the ratio of the air to the fuel, size of particles of fuel, velocity at which particles of fuel travel, and the quantity of heat generated by the electric spark. Liquid kerosene cannot be finely divided by atomizing same with a low pressure blower. There must be a pressure of at least two lbs., in order to finely divide said fuel. If the fuel is finely divided, and the common spark 80 plug (such as used on gasoline engines) is used for igniting same, I have found that the mixture of air and fuel must be rich in hydro-carbon or ignition will not take place. In order to make a completely combustible 85 mixture, an additional supply of air must be added. Any suitable means may be employed to supply this additional air; in the drawing I show a blower 39 which is driven by the electric motor 18. The resultant 90 mixture is directed to the combustion chamber 40 through the tube 41. I have found that a completely combustible mixture of air and finely divided kerosene can be ignited by a series of electric sparks, such as shown 95 in the sparking device in Figs. 2 and 3, in which 42 is a porcelain insulator containing a series of spark points 43. A number of spark tubes 42 (see Fig. 2) are required if the velocity of the mixture is high. Said 100 tubes may be joined by the insulator ring 44.

The controls for the fuel mixture of the burner, the water to the steam generator and current to the spark plug will next be described.

105 The numeral 45 indicates a storage battery which may be charged by a suitable dynamo, not shown. 46 is a manually operated switch connecting through the wire 46^a with the positive side of the battery. The 110 wire 47 is connected to an insulating screw 48. A spring held lever 49 is arranged to normally make contact with the screw 48; said lever 49 is arranged in coöperative relation with the free end of the Bourdon tube 115 10, the relation between the Bourdon tube 10 and the lever 49 being such that when the pressure of steam to which the Bourdon tube is subjected reaches a predetermined amount, the lever 49 will move away from the screw 120 48 and break the electric circuit between said screw 48 and lever 49. The wire 50 is connected to the lever 49 and leads to a point 51, at which point the circuit divides. A wire 52 connects with the wire 50 at the point 51 125 and runs to the primary winding 53 of a vibrating spark coil.

A solenoid 54 is connected in series with the wire 55 leading to the spark plug 37. The numeral 56 indicates a stationary insu- 130

lated contact which is connected to the wires 50 and 52 at the point 51 by the wire 57. The core 58 of the solenoid 54 makes contact with the part 56 and is connected to the motor 18 by the wire 59. When the normal amount of current is flowing to the spark plug 37, the spring 60 on solenoid 54 maintains the core 58 in engagement with the contact 56 and prevents the opening of the 10 circuit to the motor 18, but if an abnormal amount of current is passing through the solenoid 54 (due to a short circuit in the spark plug 37), the solenoid acts to open the circuit to the motor 18. In this operation 15 the core 58 is drawn downward against the resistance of the spring 60 to separate it from engagement with the contact 56 whereby the circuit to the motor is broken over the wire 59. Under these conditions the motor 18 (and all electrical equipment connected in series therewith) cannot operate until the spark plug 37 is restored to normal working condition.

The wire 61 leads from the motor 18 to a 25 solenoid 62. One end of the core of said solenoid 62 is connected to a brass stem 62^a (non-magnetic), of the valve 63 in the air line 32. The other end of the core of the solenoid 62 is connected to a piston 64, which 30 operates in the cylinder 65; said cylinder 65 has a small opening 66 at its lower end which connects to the atmosphere. The wire 67 from one side of the primary coil 53 is connected to the cylinder 65. The wire 35 68 is connected to the negative side of the battery 45 and runs to the insulated contact 69. The core of the solenoid 62 carries the sliding contact 70 which operates to open and close the circuit to the primary coil 53. 40 When the sliding contact 70 is in engagement with the insulated contact 69, current will flow through the coil 53 over wires 47, 50, 52, 67 and 68. When current passes through the solenoid 62 the stem 62^a will be 45 drawn to the right against the resistance of the spring 71 and the valve in the air line 32 will be opened, allowing air to pass to the nozzle 35 whereby said air will draw fuel from the nozzle 36 and atomize same; said mixture, which is rich in hydro-carbon, is 50 ignited by the spark plug 37 and additional air to form a completely combustible mixture is supplied from the motor-driven blower 39. The movement of the piston 64 55 is timed by the size of the opening 66 in the cylinder 65 in order to control the rate of movement of the contact 70 over the contact 69, and current to the primary spark coil 53 is cut off when contact 70, moves off of said 60 contact 69 after a predetermined period of time. The spring 71 returns the core of the solenoid 62 to normal position when the current is not running through the solenoid. The wire 72 connects the solenoid 62 to the 65 contact 73. The numeral 74 indicates a dia-

phragm which is pressed into contact with the insulated point 75, by the weight of the fuel in tank 33 on said diaphragm. If the fuel tank is empty the diaphragm 74 acts to break the circuit between the screw 73 and 70 the point 75. This operates to cut out the motor 18 by breaking the circuit thereto over the wire 72. The wire 76 connects to the point 75 and runs to the screw 77 on the water tank. 78 is a diaphragm which is 75 pressed into contact with the insulated point 79 by the weight of the water in tank 15. If the water tank is empty, the diaphragm 78 acts to break the circuit between the screw 77 and the point 79. This also operates to 80 cut out the motor by breaking the circuit thereto over the wires 76 and 72. The wire 80 leads from the point 79 to the negative side of the battery 45, which completes the circuit.

The water pump 17 is driven by the motor 18, and the blower 39 is also driven by said motor 18. As air to the nozzle 35 is always furnished at a constant fixed pressure (by virtue of the reducing valve 30) and is controlled by the solenoid 62 which is connected in series with the motor 18, it will be seen that the fuel to the combustion chamber and water to the generator, from pump 17, will be furnished in substantial unison and in 95 definite quantitative relation.

From the foregoing description it will be seen that after a certain pressure of steam is reached the spark plug 37 will be placed in operation, or cut out, and the air to the 100 nozzle 35, which controls the operation of the burner, and water to the generator, supplied by the action of the pump 17, will be turned on or cut off according to the demand for steam as governed by road conditions. Such instantaneous control of the spark-plug, burner, and pump is effected 105 through the action of the Bourdon tube 10, which operates, according to the pressure of steam in the generator, to make or break the 110 contact between the lever 49 and screw 48, and thereby close or open, respectively, the circuit to the motor 18, which governs the 115 operation of said spark plug, burner, and pump.

When lever 49 is in contact with screw 48, the circuit to the motor is closed from battery 45 through switch 46, wire 47, screw 48, arm 49, wire 50, wire 57, contacts 56 and 58, wire 59 and wires 61, 72, 76 and 80. 120 When the arm 49 is moved out of contact with screw 48, it is obvious that the connection between wires 47 and 50 will be broken and the motor cut out.

With the circuit closed, the solenoid 62 125 which is in series with the motor 18 will be energized to open the valve 63 and move the contact 70 into engagement with the stationary contact 69 thereby placing the primary spark coil 53 in the circuit of the bat- 130

1
terry as heretofore described. Current to the spark plug 37 then passes from the secondary coil 38 over the wire 55 through solenoid 54 to the spark plug, the return being 5 through ground. When the contacts 49 and 48 are separated, or when the sliding contact 70 passes off of the fixed contact 69, no current can pass to the coil 53 and hence the spark plug will be cut out.

10 The pump 17 is operated direct from the motor 18 by means of the shaft 19^a and worm 19, as heretofore described. When the arm 49 breaks contact with screw 48, cutting out the motor 18, it necessarily follows 15 that the pump 17 will cease to operate and the supply of water to the generator will be discontinued.

Finally, when the circuit to the motor is broken by the movement of the arm 49 out 20 of engagement with the screw 48, the solenoid 62 will be deenergized, the valve 63 closed to prevent air passage through the pipe 32 to the nozzle 35 and hence the burner will cease to function as the supply of fuel 25 to the burner is dependent upon the blast of air from the nozzle 35.

As it is desirable to change the ratio between the water supplied by pump 17 and the fuel to the combustion chamber, (under 30 different load conditions) I provide the water pump 16 as before described. I will now describe the control of the water from pump 16 to the generator coils.

I prefer to use a vapor tension thermostat 35 81 which is connected to the steam generator coils 1, in the liquid heating portion of said coils. The thermostat is subjected to temperature changes of the fluid in the generator coils 1. The pipe 82 connects the 40 thermostat 81 to the Bourdon tube 83. When a predetermined pressure is created in said Bourdon tube 83 (by reason of the high temperature in the portion of the generator where the thermostat 81 is located), said 45 tube will move the spring held lever 84 into contact with the insulated screw 85, to close an electric circuit. This circuit comprises a wire 86 connected to the arm 84 and leading to a solenoid 87, a return wire 86^a leading 50 from the solenoid 87 and connected to the wire 80 which passes to the negative side of the battery 45, wire 47 and a branch wire 47^a connecting wire 47 with the contact screw 85. The core of the solenoid 87 is connected 55 to a valve stem 87^a which controls a valve 88 in the suction line of the pump 16. A spring 89 operates normally to raise the core of the solenoid 87 and close the valve 88. When contact is made between arm 84 and 60 screw 85, due to increased temperature, the solenoid 87 will be energized and operate to draw downward stem 87^a against the resistance of spring 89 and open the valve 88 in the suction line of pump 16 so that additional water will be pumped to the gener- 65

ator until such time as the thermostat cools down and the pressure drops in the Bourdon tube 83, which latter then moves to break contact between arm 84 and screw 85 and thereby break the electric circuit to solenoid 70 87, whereupon the valve 88 in the suction line of the pump 16 will be closed automatically by action of the spring 89.

It will be seen from the foregoing that I have provided a steam generating system, 75 whereby the fuel to the combustion chamber and the water to the generator are supplied in substantial unison and in definite relations, and that said supplies are controlled instantly according to changes in the de- 80 mand for steam. I have also provided an additional water supply which operates independently of the first mentioned water supply, whereby the ratio between fuel and 85 water can be changed automatically, de- pending on the temperature at a fixed point in the steam generator coils. I have pro- 90 vided an electric system which makes the above mentioned operation instantaneous, and whereby there is a certain coöperative 95 relation between the working of each part in the system and in which the dangers of burning the generator, or flooding the generator with water, or flooding the combustion chamber with unburned fuel, have been 100 eliminated. I have also provided a means which coöperates with the regulating de- 105 vices, to store steam during periods that the generator is not working to full capacity and to return said steam to the generator coils, if there is a slight drop in pressure in 110 said generating coils, due to small inaccuracy in said regulating devices.

I have described the best embodiment of my invention now known to me; but it is to 105 be understood that the apparatus shown is merely illustrative and that the invention can be carried out by other means.

I claim:—

1. In an apparatus for generating steam, 110 a steam generator, means for supplying liquid to the generator, means for supplying a fuel mixture for heating the generator, an electrical device for igniting said fuel mixture, and means for initiating the functions 115 of the liquid and fuel supply means and the device for igniting the fuel mixture from a single source of control.

2. In an apparatus for generating steam, a 120 steam generator, operable means for sup- 125 plying liquid to the generator, operable means for supplying a fuel mixture for heating the generator, an electrical device for igniting said fuel mixture, and means functioning in the operation of the appa- 130 ratus for automatically controlling, either to turn on or to shut off in substantial unison, said electrical device, the supply of liquid to the generator and the supply of fuel for heating the generator.

3. In an apparatus for generating steam, a steam generator, an electrically driven pump for furnishing liquid to the generator, a burner, electrically controlled means for furnishing a fuel mixture to said burner, an electrical device for igniting said fuel mixture, an electrical circuit including the said electrically driven means, the controlling means for the fuel mixture and said igniting device, and a make-and-break switch in said circuit, whereby on closing said switch the supply of liquid to the generator, the supply of fuel mixture to the burner and the ignition of said fuel mixture may be occasioned in substantial unison. 75
4. In an apparatus for generating steam, a steam generator, a pump for furnishing liquid to the generator, a burner, electrically controlled means for furnishing a fuel mixture to said burner, an electrical device for igniting said fuel mixture, a blower for supplying air to the ignited mixture, a motor for simultaneously operating said pump and blower, an electrical circuit including the motor, said electrical igniting device and the controlling means for the fuel mixture, and a make-and-break switch in said circuit, whereby on closing said switch the functions of liquid supply, fuel supply, combustion, and air supply may be simultaneously initiated. 80
5. In an apparatus for generating steam, a steam generator, means for supplying liquid to the generator, means for supplying a fuel mixture for heating the generator, an electrical device for igniting said fuel mixture, and single means for automatically and simultaneously controlling said electrical device, the supply of liquid to the generator and the supply of fuel for heating the generator. 85
6. In an apparatus for generating steam, a steam generator, means for supplying liquid to the generator, means for supplying a fuel mixture for heating the generator, an electrical device for igniting said fuel mixture, and single means governed by generator conditions for automatically controlling in substantial unison said electrical device, the supply of liquid to the generator and the supply of fuel for heating the generator. 90
7. In an apparatus for generating steam, a steam generator, means for supplying liquid to the generator, means for supplying a fuel mixture for heating the generator, an electrical device for igniting said fuel mixture, and means for automatically controlling said electrical device, the supply of liquid to the generator, and the fuel for heating the generator, in substantial unison with the rise or fall in the pressure of steam above or below a predetermined degree. 95
8. In an apparatus for generating steam, a steam generator, an electrically controlled device for supplying liquid to the generator, an electrically controlled device for supplying fuel for heating the generator, an electrical device for igniting said fuel, and means governed by generator conditions for automatically closing or opening the electric circuits to said igniting device, the device for supplying liquid to the generator and the device for supplying fuel for heating the generator. 100
9. In an apparatus for generating steam, a steam generator, an electrically controlled device for supplying liquid to the generator, an electrically controlled device for supplying fuel for heating the generator, an electrical device for igniting said fuel, and means, governed by generator conditions, for automatically and simultaneously opening or closing the electric circuit to said igniting device, the device controlling the supply of liquid to the generator and the device controlling the supply of fuel for heating the generator. 105
10. In an apparatus for generating steam, a steam generator, means for supplying liquid to the generator, means for supplying a fuel mixture for heating the generator, an electrical device for igniting said fuel mixture, means for automatically controlling in substantial unison said electrical device, the supply of liquid to the generator and the supply of fuel for heating the generator, and independent means for automatically varying the relation between the supplies of liquid and fuel. 110
11. In an apparatus for generating steam, a steam generator, an electrically controlled device for supplying liquid to the generator, an electrically controlled device for supplying fuel for heating the generator, an electrical device for igniting said fuel, means governed by generator conditions for automatically controlling the operation of the three devices named, and independent means, also governed by generator conditions, for automatically varying the relation between the supplies of liquid and fuel. 115
12. In an apparatus for generating steam, a steam generator, an electrically controlled device for supplying liquid to the generator, an electrically controlled device for supplying fuel for heating the generator, an electrical device for igniting said fuel, means governed by variations in steam pressure for automatically controlling the operation of the three devices named, and independent means, governed by temperature conditions in the generator, for automatically varying the relation between the supplies of liquid and fuel. 120
13. In an apparatus for generating steam, a steam generator, means for supplying liquid to the generator, means for supplying fuel for heating the generator, an electrical device for igniting the fuel, and auto- 125
14. In an apparatus for generating steam, a steam generator, means for supplying liquid to the generator, means for supplying fuel for heating the generator, an electrical device for igniting the fuel, and auto- 130

- 6
- matic means, rendered operative by a short circuit in said igniting device, for shutting off the supply of fuel and liquid in substantial unison.
- 5 14. In an apparatus for generating steam, a steam generator, means for supplying liquid to the generator, a tank for containing the liquid, means for supplying fuel for heating the generator, a cut-off device associated with said liquid tank, and automatic means for shutting off the fuel rendered operative by said cut-off device when the liquid in the liquid tank has fallen to a predetermined level.
- 10 15. In an apparatus for generating steam, a steam generator, means for supplying liquid to the generator, means for supplying fuel for heating the generator, a tank containing said fuel, a cut-off device associated with said fuel tank, and automatic means for shutting off the liquid to the generator rendered operative by said cut-off device when the fuel in the fuel tank has fallen to a predetermined level.
- 15 16. In an apparatus for generating steam, comprising a steam generator, a combustion chamber arranged in coöoperative relation with the same, and a steam engine connected to the steam delivering pipe of said generator, a liquid supply for the generator comprising two water pumps and their connections to a source of liquid, one of said pumps being driven from said engine, a fuel supply to the combustion chamber, an electric device for igniting the fuel, means for automatically controlling the liquid supply from one of said pumps, the fuel supply and said electrical device in substantial unison and in accordance with generator conditions, and independent means for automatically controlling the supply of liquid from the other pump according to generator conditions.
- 20 17. In an apparatus for generating steam, a steam generator, a fuel supply for heating the generator, an electrical device for igniting the fuel, a liquid supply for the generator comprising two water pumps, a steam engine for driving one of said water pumps, an electric motor for driving the other pump, means for controlling the electrically driven water pump, the fuel supply and said electrical device in substantial unison, said means being brought into operation by generator conditions and independent means for automatically controlling the liquid from the steam engine driven pump according to generator conditions.
- 25 18. In an apparatus for generating steam, a steam generator, a fuel supply for heating the generator, an igniting device for the fuel, a pump for furnishing water to the generator, and means governed by generator conditions for automatically controlling in substantial unison the operation of said igniting device, said pump and the fuel supply.
- 30 19. In an apparatus for generating steam, a steam generator, a fuel supply for heating the generator, an igniting device for the fuel, a pump for furnishing water to the generator, and means rendered operative by the rise or fall in steam pressure in the generator above or below a prescribed range for automatically controlling the operation of said igniting device, said water pump and the fuel supply in substantial unison. 70
- 35 20. In an apparatus for generating steam, a steam generator, an electrically controlled fuel supply for heating the generator, an electrical igniting device for the fuel, an electrically driven pump for furnishing water to the generator, an electrical circuit including the electrical driving means, the fuel supply control and the igniting device, and means governed by generator conditions for opening and closing said circuit whereby 80 automatically control said pump, fuel supply and igniting device.
- 40 21. In an apparatus for generating steam, a steam generator, a fuel supply for heating the generator, an electrical device for igniting the fuel mixture, a liquid supply for the generator comprising two water pumps and their connections to a source of liquid, a steam engine for driving one of said pumps, an electric motor for driving the other pump, means rendered operative by the rise or fall in steam pressure in the generator above or below a prescribed range for controlling the supply of fuel, said electrical device and the supply of liquid from 90 the electrically driven pump, and means rendered operative by the rise or fall in the temperature of the fluid in the generator above or below a prescribed range for controlling the supply of the liquid to the generator from the steam engine driven pump. 95
- 45 22. In an apparatus for generating steam, a steam generator, means for supplying liquid to the generator, means for supplying fuel for heating the generator, an electrical device for igniting the fuel mixture, means governed by generator conditions for automatically controlling the electrical device and the fuel and liquid supplies in substantial unison, and means for automatically adding an additional supply of liquid to the generator in accordance with generator conditions. 100
- 50 23. In an apparatus for generating steam, a steam generator, means for supplying liquid to the generator, means for supplying fuel for heating the generator, an igniting device for the fuel, means rendered operative by the rise or fall in the steam pressure in the generator above or below a prescribed range for controlling the supply of fuel, said igniting device and the supply of liquid, an additional liquid supply for said generator, and means rendered operative by the rise or fall in temperature of 110
- 55 120
- 60 125
- 65 130

the fluid in the generator above or below a prescribed range for automatically controlling said additional liquid supply to the generator.

- 5 24. In an apparatus for generating steam, a steam generator, means for supplying a liquid thereto, an electrical device for controlling said supply of liquid, means for supplying fuel for heating the generator, an 10 electrical device for controlling said supply of fuel, an electrical device for igniting the fuel, and means rendered operative by a fall in steam pressure in the generator below a given amount for bringing said devices into operation.

- 15 25. In an apparatus for generating steam, a steam generator, means for supplying a liquid thereto, an electrical device for controlling said supply of liquid, means for 20 supplying fuel for heating the generator, an electrical device for controlling the supply of fuel, an electrical device for igniting the fuel, means rendered operative by a fall in the steam pressure in the generator 25 below a given amount for bringing said devices into operation in substantial unison, an additional liquid supply for the generator, an electrical device for controlling said additional liquid supply, and means 30 rendered operative by a rise in temperature of the liquid in the generator above a given degree for bringing said additional liquid-supply controlling device into operation.

- 35 26. In an apparatus for generating steam, a steam generator, comprising a plurality of pipe coils connected in series, means for supplying liquid to the generator, means for supplying a fuel mixture for heating the generator, an electrical device for igniting 40 the fuel mixture, and single means governed by generator conditions for automatically controlling in substantial unison said electrical device, the supply of liquid to the generator and the supply of fuel for heating 45 the generator.

27. In an apparatus for generating steam, a steam generator of the flash type, an elec-

trically controlled device for supplying liquid to the generator, an electrically controlled device for supplying fuel for heating the generator, an electrical device for igniting the fuel, and means governed by generator conditions for automatically controlling said devices.

28. In an apparatus for generating steam, 55 a steam generator of the flash type, an electrically controlled device for supplying liquid to the generator, an electrically controlled device for supplying fuel for heating the generator, an electrical device for igniting the fuel, means governed by generator 60 conditions for automatically controlling said devices in substantial unison, and independent means for automatically changing the relation between the supplies of 65 liquid and fuel.

29. In an apparatus for generating steam, a steam generator, means for supplying liquid to the generator, means for supplying fuel for heating the generator, an electrically controlled device for igniting said fuel, and means for initiating the functions 70 of the liquid and fuel supply means and the device for igniting the fuel from a single source of control.

30. In an apparatus for generating steam, a steam generator, an electrically controlled device for supplying liquid to the generator, an electrically controlled device for supplying fuel for heating the generator, an electrically controlled device for igniting said fuel, and means governed by generator conditions for automatically opening and closing the electrical circuit to said igniting device, the device for supplying liquid to the 85 generator and the device for supplying fuel for heating the generator.

In witness whereof I have hereunto set my hand this 5th day of February, 1918.

LEWIS L. SCOTT.

Witnesses:

MELBA S. STUMPF,
GAIL MAGUIRE.
